RESILIENT SASH BEARING

Fred Booth, Jr., Los Angeles, Calif., assignor to
Duplex Incorporated, Los Angeles, Calif., a cor-
poration of California

Application September 28, 1945, Serial No. 619,091

2 Claims. (Cl. 292—76)

1

My invention relates to window fixtures and has particular reference to a resilient bearing device for holding a sliding window sash in normal position.

Various means have been devised as substitutes for the old sash-weight counter-balance for windows, among which has been the use of a spring-actuated drum type balance wherein one end of a sash supporting band is attached to the window sash and the other end to a spring-actuated drum. While balances of this kind are satisfactory for the purpose of counter-balancing the weight of the sash, they have a tendency to tilt or rotate the sash in the frame about a horizontal axis and throw the upper corner on the side opposite the point of counter-balance support into corner-wise engagement with the window frame or sash guide. When the sash is tilted in this manner, it tends to bind in the frame and will not slide up and down with sufficient ease. To offset this tendency a resilient bearing has been utilized for application to the sash near the corner. To date however, the particular style of resilient bearing has been of a composite construction which has been prone to become dislodged from proper adjustment and to need frequent re-adjusting, or possessed other deficiencies. The composite construction of the prior art devices has also raised the cost of window hardware to a figure higher than justified in view of the simple operative essentials of a device of this kind.

It is therefore among the objects of the invention to provide a new and improved resilient bearing for window sashes which is simple in construction, efficient in performance and relatively inexpensive to manufacture.

Another object of the invention is to provide a new and improved resilient bearing for window sashes which can be applied, removed and adjusted from the exterior without it being necessary to remove the window sash from a frame, and of great importance, a bearing which inherently provides a self-adjustment to a considerable degree, offering varying degrees of resistance depending upon the operating proximity and pressure between window sash and sash guide or frame.

Still another object of the invention is to provide a new and improved resilient bearing device of a leaf or ribbon spring construction having a two point bearing under compression so that the spring action is smooth and well distributed regardless of how greatly the spring may be compressed by the tilt of a window sash to which it is attached.

2

A further object of the invention is to provide a new and improved resilient bearing device of leaf or ribbon spring construction applicable at the corner of a window sash for frictionally guiding the sash in the frame and so designed and mounted that the spring element at the same time serves as a snubber preventing the corner of the sash from gouging the adjacent surface of the frame.

With these and other objects in view, the invention consists in the construction, arrangement and combination of the various parts of the device, whereby the objects contemplated are attained, as hereinafter more fully set forth, pointed out in the claims and illustrated in the accompanying drawing, in which:

Figure 1 shows a sliding window sash mounted in a frame with the surrounding casing broken away showing the location of the novel fixture incorporating the invention.

Figure 2 is an enlarged fragmentary longitudinal sectional view showing the fixture mounted on a window sash as viewed from the rear.

Figure 3 is a view similar to Figure 2 showing the spring fixture under greater compression due to rotation of the sash.

Figure 4 is a side elevational view of the fixture prior to its application to a window sash.

Figure 5 is a top view of the fixture shown in Figure 4.

Figure 6 is a perspective view of the fixture.

In the manufacture of window hardware several factors must be taken into consideration, namely the provision of durable hardware which will not deteriorate under long periods of use, hardware of simple construction so that a mechanic can install it with ease and at a minimum expenditure of time and also hardware of such simple design and operation that it will work smoothly and efficiently on all occasions without becoming dislodged from proper adjustment.

A simple device incorporating these several desirable features and capable of accomplishing the objects sought there has been selected and illustrated in the drawing as an embodiment of the invention. The device comprises a resilient bearing device 10, shown in detail in Figures 4, 5 and 6 illustrated in its assembled relationship with a window sash 11 and frame or sash guide 12 in Figures 1, 2, and 3.

In a building structure incorporating the window sash and frame there is shown a window casing 13 within which is mounted an upper sliding sash 14 in addition to the sash 11 which is positioned at the lower portion of the casing.

To provide a counter-balance for the window a spring counter-balance unit 15 is mounted upon the frame on the left hand side, as viewed in Figure 1, from which extends a supporting band 16 which is attached underneath an adjacent lower corner 17 of the sash and there permanently held in place by some suitable anchoring device. Details of the counter-balance unit and supporting band have been omitted inasmuch as this portion of the device may be of conventional construction.

When a spring counter-balance of this sort is used only one is necessary to assist in the raising of the window sash. However, when only one supporting band is applied to one side of a window sash, tension on the supporting band tends to rotate the sash about a horizontal axis in a clockwise direction, as viewed in Figure 1. This tendency to rotate would normally draw the corner 17 against the adjacent side of the frame and a corner 18 of the sash against an opposite side of the frame. The obvious result of this would be to jam the sash between the sides of the frame.

To overcome this tendency, the resilient bearing device comprising the subject matter of this invention, is applied to the corner 18 and in operative position tends to yieldably force the corner away from the adjacent side of the frame.

In order that the action may be positive, efficient and reliable the resilient bearing device has a special construction and should be attached to the sash in a proper manner.

The bearing device, before application to a window sash, comprises a leaf or ribbon spring member having a flat portion 20 incorporating means for attaching the flat portion to a window sash, herein illustrated as a pair of longitudinally spaced apertures 21 and 22. In the claims I refer to the portion 20 as a flat anchor terminal section. Immediately adjacent the flat portion is a rounded portion or arcuate bend 23 while adjacent the arcuate bend 23 the spring is bent into a concavo-convex configuration 24, the convex side of which is directed inwardly. This is referred to in the claims as a reverse direction bend forming a first bearing point (located at the lead line from numeral 24).

Next to the concavo-convex configuration is a relatively long curved portion or loop 25, the chord of which extends at an obtuse angle with relation to the flat portion 20 when the bearing is free from engagement in a window structure. At the outer end of the relatively long curved portion is a preferably although not essentially, slightly rounded, free end 26 to provide a smooth sliding engagement with a window sash when in assembled relationship. This free end is referred to in the claims as a second bearing point.

Whereas I have spoken of an arcuate portion, it is to be taken in the broadest sense in that it may also be what is known as a compound curve; that is, it need not have a common center or radius of curvature.

The rounded portion 23 is of a material radius. By "material" is meant a radius many times larger than the thickness of the material being used to form the device herein described. I contemplate a radius large enough to furnish under certain conditions a bearing surface and purposely so designed for such use, rather than a radius which results from the fact that the type of material used cannot be formed into a square corner.

When the device is to be applied to a window

5 sash the sash, if desired, may first be mounted in a window frame and the casing attached. There will always be a certain space 27 allowed between the edge of the sash and the adjacent edge of the frame 12. The bearing is attached to the corner of the sash, in this particular embodiment, by means of nails 28 which are driven through the apertures 20 and 21 into a horizontal element or rail 29 of the sash. By the use of two nails the bearing is prevented from being cocked out of position once it is secured in place. The bearing 10 may be mounted on the sash before it is installed, if desired. When mounted, the spring is sprung vertically away from the rail of the sash as shown in Figure 2.

When the bearing is properly mounted and the sash is in, the loop 25 extends into the space 27 and in this position is bent so that the chord of the loop is substantially at right angles to the direction of the straight portion 20. The convex side of the loop will bear resiliently against the adjacent face of the frame or sash guide 12.

Thus mounted, the rounded corner or arcuate bend 23 surrounds the corner 18 of the sash and may be in contact with it and the bearing point 24 between the arcuate bend and the loop 25 is positioned close to but not necessarily in engagement with the adjacent surface of the sash. In this position also the free terminal end 26 will be in frictionally slideable contact with the sash.

20 When the sash is in operating proximity to the sash guide or frame 12 pressure will be exerted against the bearing, first at the end or bearing point 26 and then, if the pressure increases, against the concavo-convex portion or bearing point 24. The configuration of the spring may be such that the order of contact of the bearing points is reversed, or it may be simultaneous. Since the convex side of the long arcuate portion or loop is already in contact with the adjacent surface of the frame or sash guide, it will tend to press with increasing force against the frame. There will consequently be a broad frictional contact at the convex side of the loop and eventually a two point support at the ends of the loop 30 against the sash. A further increase in pressure will tend to flatten the loop to a slightly greater extent and at the same time push the bearing point 26 and the concavo-convex portion 24 endwise. Should the pressure be increased by mutual approach of sash and guide the convex surface of the arcuate bend 23 may come into bearing contact with the guide.

To readjust the tension of the spring in relation to the surrounding sash and frame it is necessary only to withdraw the nails 28, or screws if screws be used, shift the straight portion of the bearing to the right or left as the case may be and then reapply the nails. The bearing may be moved either towards the right or towards the left to respectively decrease or increase spring pressure exerted by the bearing. It is clear also that the bearing may be removed by a similar withdrawal of the nails and replaced by a new bearing having a greater or a lesser spring tension as may be required.

It should be noted that the anchor terminal section will usually be mounted on the sash rail at a location spaced away from the arcuate bend 23, and when thus anchored the spring at an intermediate point in the arcuate bend preferably although not necessarily contacts the corner of the sash but the radius and arc of said bend are such that the spring is sprung vertically 40 away from the rail of the sash and outwardly

away from the side of the sash and when not in operating proximity to a sash guide neither of the first or second bearing points is in contact with the sash, and when the mounted spring is in operating proximity to a sash guide the convex surface of the loop yieldably presses against the guide and the second bearing point engages the side of the sash, and if pressure between guide and sash is sufficient to overcome the spring resistance thus offered, the first bearing point engages the side of the sash and thus shortens the effective length of the spring and increases the resistance thereof.

There has been accordingly provided a resilient bearing device of extremely simple construction but in which is incorporated configurations of special importance which permits the bearing to efficiently perform its several functions while enabling it to be made simply and inexpensively and capable of installation with a minimum of expenditure of effort. The flat anchor section of the bearing obviously can be attached at the top or bottom of a vertically slideable window or at the sides of a horizontally slideable window. The description in the claims assumes a position of the bearing with the flat anchor surface attached either to the top or bottom of a sash.

Although I have herein shown and described my invention in what I have conceived to be the most practical and preferred embodiment, it is recognized that departures may be made therefrom within the scope of my invention, which is not to be limited to the details disclosed herein but is to be accorded the full scope of the claims so as to embrace any and all equivalent structures.

Having thus described my invention, what I claim as new and desire to secure by Letters Patent is:

1. A resilient sash bearing comprising a ribbon spring which when in equilibrium comprises a flat anchor terminal section, an arcuate bend extending outwardly and laterally from one end of the terminal section, a reverse direction bend forming a first bearing point at the free extremity of the said arcuate bend, a loop bowed in the same direction as the arcuate bend and longer than the same and extending laterally and outwardly from the reverse direction bend, the terminal end of the loop forming a second bearing point, the said loop lying in a general plane at an obtuse angle to the anchor terminal section, the said anchor terminal section being adapted to be mounted horizontally on a rail of a sash at a location spaced away from the arcuate bend, and when thus anchored the spring at an intermediate point in the said arcuate bend may contact the corner of the sash but the radius and arc of said bend are such that the spring is sprung vertically away from the rail of the sash and outwardly away from the side of the sash and when not in operating proximity to a sash guide neither of said first or second bearing points is in contact with the sash, and when the mounted spring is in operating prox-

imity to a sash guide the convex surface of the loop yieldably presses against the guide and the second bearing point engages the side of the sash, and if pressure between guide and sash is sufficient to overcome the spring resistance thus offered, the said first bearing point engages the side of the sash and thus shortens the effective length of the spring and increases the resistance thereof.

- 10 2. A resilient sash bearing comprising a ribbon spring which when in equilibrium comprises a flat anchor terminal section, an arcuate bend extending outwardly and laterally from one end of the terminal section, a reverse direction bend forming a first bearing point at the free extremity of the said arcuate bend, a loop bowed in the same direction as the arcuate bend and longer than the same and extending laterally and outwardly from the reverse direction bend, the terminal end of the loop forming a second bearing point, the said loop lying in a general plane at an obtuse angle to the anchor terminal section, the said anchor terminal section being adapted to be mounted horizontally on a rail of a sash at a location spaced away from the arcuate bend, and when thus anchored the spring at an intermediate point in the said arcuate bend may contact the corner of the sash but the radius and arc of said bend are such that the spring is sprung vertically away from the rail of the sash and outwardly away from the side of the sash and when not in operating proximity to a sash guide neither of said first or second bearing points is in contact with the sash, and when the mounted spring is in operating proximity to a sash guide the convex surface of the loop yieldably presses against the guide and at least one of said bearing points engages the side of the sash, and if pressure between guide and sash is sufficient both said bearing points engage the side of the sash, the radius and arc of said arcuate bend being proportioned and located relative to the said loop so that the convex surface of said bend is adapted to resiliently bear against the sash guide upon increase of pressure between sash and guide sufficient to overcome the resistance of the spring established upon contact of both said bearing points with the sash.
